UNITED STATES PATENT OFFICE

133,397

DESIGN FOR A FINGER RING

Marcel Boucher, New York, N. Y.

Application July 13, 1942, Serial No. 107,502

Term of patent 3½ years

To all whom it may concern:

Be it known that I, Marcel Boucher, a citizen of the United States, residing in New York city, in the county of New York and State of New York, have invented a new, original, and ornamental Design for a Finger Ring, of which the following is a specification, reference being had to the accompanying drawing, forming part thereof.

Fig. 1 is a top plan view of a finger ring showing my new design,
Fig. 2 is an elevational front view thereof, and
Fig. 3 is an elevational side view thereof.

The reverse side of Fig. 2 is the same.

I claim:

The ornamental design for a finger ring, substantially as shown and described.

MARCEL BOUCHER.
